Application December 24, 1954, Serial No. 477,466

19 Claims. (Cl. 200—148)

This invention relates to circuit interrupters in general, and, more particularly, to arc-extinguishing structures therefor.

United States patent application Serial No. 686,775, filed September 27, 1957, is a division of the present application.

A general object of our invention is to provide an improved and highly effective circuit interrupter, which will interrupt the circuit therethrough more effectively than have circuit interrupters heretofore.

A more specific object of our invention is to provide an improved circuit interrupter, particularly one of the gas-blast type, in which advantage is taken of the grounded metallic tank structure generally employed in the high-voltage, oil-circuit-interrupter tank art.

Another object of our invention is to take advantage of the unusual and phenomenal dielectric properties, and arc-extinguishing characteristics, of sulfur hexafluoride or selenium hexafluoride, particularly when these gases are utilized in conjunction with a grounded metallic tank structure.

Still a further object of our invention is to provide an improved compressed-gas circuit interrupter, in which contact operation and/or fluid flow is obtained by utilizing the compressed state of the gas.

Still a further object of our invention is to provide an improved circuit interrupter including a housing containing gas under pressure, in which fluid motion is obtained by exhausting from the tank cooled fluid, as distinguished from arc-heated fluid, to bring about improved performance.

An ancillary object of our invention is to adapt sulfur hexafluoride or selenium hexafluoride gas to tank-type, grounded, metallic structures, in which preferably the gas is maintained at atmospheric, or higher pressures, within the tank to take advantage of its dielectric strength.

Further objects and advantages will readily become apparent when reading the following specification, taken in conjunction with the drawings, in which:

Figure 1 is a side elevational view, partially in vertical section, of a tank-type circuit interrupter embodying the principles of our invention, and shown in the closed-circuit position;

Fig. 2 is a fragmentary, enlarged, vertical sectional view through one of the arc-extinguishing units of the circuit interrupter of Fig. 1, the contact structure being shown in the closed-circuit position;

Fig. 3 is an enlarged, vertical sectional view through a modified type of arc-extinguishing unit, which may be substituted for the units illustrated in Figs. 1 and 2, the contact structure being shown in the closed-circuit position;

Fig. 4 is another modified type of arc-extinguishing unit, which may be substituted for the units of Figs. 2 and 3, the contact structure shown at an intermediate point in the opening operation;

Fig. 5 is a substantially vertical sectional view through a modified type of circuit interrupter, with the arc-ex-

2

tinguishing units being illustrated in side elevation, and the contact structure being shown in the closed-circuit position;

Fig. 6 is a fragmentary, enlarged, vertical sectional view through the left-hand arc-extinguishing unit of the circuit interrupter illustrated in Fig. 5;

Fig. 7 illustrates a modified type of exhaust valve operating arrangement, which may be utilized in conjunction with the arc-extinguishing unit illustrated in Fig. 6;

Fig. 8 is an enlarged, fragmentary, vertical sectional view through a modified type of exhaust-valve operating arrangement, which is directly connected to the valve operating rod, and which may be substituted for the exhaust-valve operating arrangements of Figs. 6 and 7;

Fig. 9 is a fragmentary, enlarged, vertical sectional view through a modified type of arc-extinguishing unit, which may be substituted for the arc-extinguishing units, illustrated in Figs. 5 and 6, the contact structure being shown in the partially open-circuit position;

Fig. 10 is a fragmentary, vertical sectional view through yet another modified type of arc-extinguishing unit, which may be substituted for the unit illustrated in Fig. 9 of the drawings; and,

Fig. 11 is a fragmentary, vertical sectional view through still another modified type of arc-extinguishing unit, the contact structure being illustrated in the partially open-circuit position.

In U.S. patent application filed July 19, 1951, Serial No 237,502, now United States Patent 2,757,261, issued

July 31, 1956, to Harry J. Lingal, Thomas E. Browne, Jr., and Albert P. Strom, and assigned to the assignee of the instant application, the remarkable arc-extinguishing characteristics of sulfur hexafluoride gas are described. It is known that this gas has a dielectric strength equal

to that of insulating oil at slightly elevated pressure (2.5 to 3 atmospheres absolute) and so may be directly substituted for oil as an insulating medium in circuit breakers, and the like, if it can be maintained at the elevated pressure. We have discovered the fact, demonstrated in experimental studies, that SF₆ gas at moderate pressures may be employed in fluid-flow type circuit interrupting devices similar to those ordinarily filled with oil with comparable effect. It has been shown particularly that in such devices, which cause a definite volume of fluid to flow

45 through a channel surrounding the arcing contacts, effective interrupting performance can be obtained with total displaced volume of SF₆ gas no larger than the volumes of oil ordinarily displaced.

The use of SF₆ gas instead of oil in structures resembling 50 those used with oil offers many advantages:

(1) The gas medium is non-inflammable, and hence eliminates the explosion and fire hazard.

(2) Its lower density reduces the forces required to move it, and so can aid in achieving highest possible operating speeds.

(3) Compressibility of the gas serves to cushion the pressure shocks produced by the sudden drawing of high-current arcs in a confined fluid. The control of these explosive pressures in structures filled with nearly incompressible oil is a critical problem in the development of circuit breakers for the highest powers.

(4) The use of steel tanks fitted with high-voltage bushings, the common practice with oil circuit breakers, offers many practical advantages for a gas-filled breaker also.

65 The use of SF₆, under a few atmospheres pressure, promises to permit the retention of these practical advantages, especially (a) the availability of inexpensive bushing-type current transformers as a part of the breaker, (b) the "dead-tank" feature increasing safety against electrical hazards, and (c) the mechanical ruggedness and resistance to explosion of steel containers, which also serve as supporting structures.

(5) If desired, the tanks for SF₆ may be made smaller than for oil by using sufficiently elevated gas pressures to achieve dielectric strengths higher than that of oil.

(6) Energy for producing fluid flow, contact motion, or both, can be stored in the contained gas by virtue of its compression, eliminating the necessity for large springs in the breaker mechanism.

(7) Decomposition products caused by arcing do not include carbon and are all good electrical insulators. The chemical activity of the gaseous products, and the inertness of the SF₆, makes possible absorption of these gaseous products simply by providing some inert solid materials (e.g., activated alumina) within the enclosure in contact with the gas. This should make possible longer periods of use of the breaker before the necessity for replacing or reconditioning the interrupting medium, or cleaning internal insulating surfaces.

(8) For the same amount of arcing, erosion of the contact surfaces should be less with gas than with liquid filling. This is especially true for capacitor switching, where contact erosion under oil is a serious problem.

To make most effective use of the gaseous medium, certain modifications of interrupting structures generally used under oil are needed. We have found that contact between the arc and organic materials should be avoided, as pointed out in the aforesaid patent. Hence, such arc controlling parts as orifices, splitters and the inner walls of arc boxes should be made of inorganic insulating materials like polytetrafluoroethylene. For conducting parts, aluminum may be preferable to copper or brass. Because of the high mobility or wandering tendency exhibited by arcs in this gas, the arc space may need to be more definitely restricted than is necessary with oil filling.

Figures 1 through 11 illustrate interrupter designs, which embody the above principles, and so are particularly suited to use in metal-enclosed circuit breakers, filled with SF₆ or SeF₆ gas at atmospheric, or higher pressures.

A relatively simple form of tank-enclosed SF₆ or SeF₆ flow interrupter is illustrated in Figs. 1 and 2 of the drawings. Referring to these figures, it will be observed that a grounded, metallic tank 1 is filled with sulfur hexafluoride or selenium hexafluoride gas at atmospheric, or higher pressures, and has extending within it a pair of terminal bushings 2, 3 of the type generally used in the oil-circuit-breaker art.

Depending from the interior ends of the terminal bushings 2, 3 are a pair of serially connected arc-extinguishing units, generally designated by the reference numeral 4, and electrically interconnected by a conducting cross-bar 5. The conducting cross-bar 5 may be vertically actuated, in the opening and closing movements, by an insulating lift rod 7, which may be operated by a suitable mechanism. As shown, the interrupting units 4 are mounted on the lower ends of bushings 2, 3 projecting into the enclosing tank 1, and the circuit is completed by the conducting cross-bar 5 movable by the insulating lift rod 7 operated by a mechanism, exactly as is commonly done in oil-circuit breaker practice, except that the tank 1 must be sealed against gas leakage at the bushing and mechanism entry points. The gas sealed within the tank 1 may be at atmospheric pressure, but preferably should be compressed to at least two or three atmospheres absolute pressure.

The interrupter, as shown, is of the "puffer" type, having a movable orifice 8 and piston 9 movable within an insulating operating cylinder 10. A movable contact 11 cooperates with a stationary contact 12 and is preferably moved downwardly, in the opening direction, by a battery of compression springs 13. The compression springs 13 seat at their upper ends against the bottom 14 of the operating cylinder 10, and have their lower seats on a spring base 15, threadedly secured to the movable contact rod 16.

The extremity 17 of the cross-bar 5 strikes the contact

or piston rod 16, and moves it upwardly to the closed-circuit position as shown, against the opposition afforded by the battery of compression springs 13. During the opening operation, the lift rod 7 moves downwardly, as caused by the operating mechanism not shown, and permits the compression springs 13 to extend, driving the contact or piston rod 16 downwardly and carrying with it the movable piston 9 and the orifice 8, compressing the gas within the region 18 below the piston 9 and causing it to flow upwardly through the orifice 19.

Vents 20 are provided at the upper end of the extinguishing unit 4 for permitting the heated gas to expand if necessary to the region within the tank 1.

The interrupter 4 has been demonstrated in the laboratory to have remarkable interrupting performance. With an orifice diameter of only $\frac{5}{8}$ inch, it has successfully interrupted low-power-factor currents up to 3100 amperes at 90,000 volts single phase with SF₆ gas pressure of 15 p.s.i. gauge. For application to a circuit breaker for the largest interrupting ratings, the orifice diameter 19 would be increased, possibly to two inches, and the piston diameter to say 10 inches. It is apparent in Figs. 1 and 2 that the moving contact 11 is held closed by the cross-bar 5, and compression springs 13 serve to move the contact 11 and piston 9 to the open position when the cross bar is released. Further additional motion of the cross-bar 5 beyond the limit of the piston stroke provides an additional isolating break, as shown by the dotted lines 22 in Fig. 1.

To effect the closing of the interrupter, the interrupter mechanism moves the insulating lift rod 7 upwardly, compressing the springs 13 and effecting contact engagement between the cooperating stationary and movable contacts 12, 11 respectively. To reduce the shock of the piston 9 at the end of its opening stroke, a cushion 21 may be provided, formed of any suitable resilient material.

Fig. 3 is an enlarged vertical section view taken through a modified type of arc-extinguishing unit 23, which may be substituted for the unit 4 of Figs. 1 and 2. It will be noted that the interrupting unit 23 is not provided with compression springs, as was the case with the unit of Fig. 2. Instead, as shown in Fig. 3, the contact-carrying piston 9 is pulled to the open position by the cross-bar 5 through latches 24, which are released by cams 25 at the end of the piston stroke, permitting the cross-bar 5 to move down farther and so to provide an isolating break.

The cams 25 are provided by downwardly extending insulating strips 26, which are fastened by screws 27 to the bottom 14 of the insulating operating cylinder 10. The latches 24 are biased apart by a compression spring 28 so that the rollers 29 will maintain engagement with the cam surfaces 25.

During the closing operation, the conducting cross-bar 5 moves upwardly, as effected by the operating mechanism. The noses 30 of the latches 24 reengage the notches 31 provided at the lower end of the contact rod 16a, and the cross-bar 5 forces the piston and contact assembly 9 upwardly effecting reengagement between the movable and stationary contacts 11, 12, as shown in Fig. 3. Again a cushion 21 may be provided to limit any shock occurring at the extreme end of the piston opening movement.

Fig. 4 shows an arrangement, which is generally similar to that illustrated in Fig. 3, but incorporates a compression spring 32, which serves to retrieve or retract the piston 9 following release of the latches 24 by the cams 25.

Fig. 4 illustrates the position of the several parts when the releasing action has just taken place and prior to the return movement of the piston 9. Thus, the compression spring 32, disposed within the insulating cylinder 10, returns the moving contact rod 16a and piston 9 to the closed position, after release of the latches 24.

This would increase the isolating break distance for the same cross-bar stroke, and would cause final closure of the circuit to occur, upon closing the breaker, at the isolating break outside of the interrupting unit, generally designated by the reference numeral 33.

Fig. 5 illustrates a vertical sectional view through a modified tank structure, with the arc-extinguishing units 35 being shown in side elevation. It will be noted that each of the terminal bushings 36, 37 is provided with an exhaust passage 38 extending through the tubular conducting stud 39 passing interiorly within the terminal bushing 36, 37.

A conducting cross-bar 40 electrically interconnects in series the two modified arc-extinguishing units 35, being actuated by an insulating lift rod 41. The upper end of the lift rod 41 is diagrammatically indicated as being actuated by an armature 42, associated with a closing solenoid 43. Thus, energization of the solenoid 43 will cause the armature 42 to move upwardly, and so cause closing motion of the conducting cross-bar 40. An opening spring 45 may be provided to effect opening motion of the cross-bar 40 following deenergization of the closing solenoid 43. However, our invention is not particularly concerned with the operating mechanism for the lift rod 41, and any suitable mechanism may be employed.

Fig. 6 more clearly illustrates the internal construction of the modified type of arc-extinguishing unit 35. With particular reference to this figure, it will be noted that there is a valve operating rod 44, which makes abutting relation with the cross-bar 40 near the end of the closing stroke. The valve operating rod 44 is biased downwardly by a compression spring 46, which seats at its upper end against a laterally extending lug 47, which may be formed integrally with the metallic operating cylinder 48. The lower end of the compression spring 46 seats upon a flange member 49, secured to, and movable with, the valve operating rod 44. The upper end 50 of the valve operating rod 44 abuts against a cap 51, forming a lower seat for a second compression spring 52, the latter biasing a pilot exhaust valve 53 in such a direction as to open an exhaust port 54, and to close an inlet port 55. The pilot exhaust valve 53 includes a double-acting valve member 56, which is guided by a guide portion 57, constituting an integral part of a casting member 58.

The casting member 58 provides an exhaust passage 59, which communicates with the exhaust passage 38 extending through the terminal bushings 36, 37.

Associated with the casting member 58 is a main valve piston 60, which comprises a piston portion 61 and a main exhaust valve portion 62. A port 63, in the casting member 58, provides an entrance for high-pressure gas from the region 64 within the tank 1 (Fig. 5) to the left-hand side of the piston member 61 at all times. As will become more apparent hereinafter depending upon the operation of the pilot exhaust valve 53, atmospheric pressure, or high-pressure gas will be present in the region 65 on the right-hand side of the piston member 61.

The main valve piston 60 has a valve stem 66 associated therewith of a reduced cross-section, as compared to the cross-section of the opening 67 through which it passes. Thus, high-pressure gas from the region 64 may pass through the port 63, and through the annular area 68 about the restricted portion 69 of the valve stem 66, to enter into the region 70 on the top side of the operating piston 71. The operating piston 71 moves within the operating cylinder 48, and is spring-biased to its lower position, as shown in Fig. 6, by a compression spring 72. The operating piston 71 effects upward travel of an orifice structure 73, including a piston 74 movable within an insulating operating cylinder 75. Associated with the orifice structure 73 is a movable contact 76, which makes engagement with a second movable contact 77. The

movable contact 77 has a lost-motion connection 78 with the cross-bar 40. The lost-motion connection 78 includes a spring casing 79, fixed to the extremity of the cross-bar 40, and enclosing a compression spring 80, which seats at its lower end against the cross-bar 40. The upper end of the compression spring 80 seats against a flange 81, secured to, and movable with, the movable contact 77.

In the closed-circuit position of the modified type of arc-extinguishing unit 35, it will be obvious that the circuit therethrough includes the conducting stud 39, a conducting adaptor head 82, the casting member 58, a flexible connector 83 to the movable contact 76. The circuit then extends through the second movable contact 77 and through the conducting cross-bar 40 to the right-hand arc-extinguishing unit 35 (Fig. 5), through which the circuit extends in an identical manner to the right-hand terminal bushing 37.

To effect the opening of the arc-extinguishing unit 35 it is necessary to effect downward opening travel of the insulating lift rod 41. This will cause corresponding downward movement of the cross-bar 40. The downward motion of the cross-bar 40 will permit the compression spring 46 to move the valve operating rod 44 downwardly, thereby permitting the compression spring 52 to close off the inlet port 55 and to open the exhaust port 54 associated with the pilot exhaust valve 53.

The opening of the exhaust port 54 will vent, or exhaust, the region 65 to the right of the piston portion 61 of main valve piston 60 to permit the high-pressure gas, constantly within the region 84, to move the main valve piston 60 toward the right, thereby opening the main exhaust valve 62. This will exhaust the region 70 above the operating piston 71 through the exhaust passage 59. Since the region 85, below the operating piston 71, is at high pressure, as afforded by the ports 86 in the operating cylinder 48, the operating piston 71 will be forced upwardly by the high-pressure gas present within the region 85.

The upward movement of the main operating piston 71 will carry with it the orifice structure 73, including the piston 74, compressing the gas within the region 87 below the fixed perforated plate 88, to cause the gas to flow in the direction, as indicated by the arrows 89 in Fig. 6.

It will be obvious that following the take up of the lost-motion 78, during the initial downward movement of the cross-bar 40, the movable contact 77 will be carried therewith downwardly to the open-circuit position. Thus, the arc, which is established between the two movable contacts 76, 77, will be rapidly lengthened, and simultaneously subjected to a flow of gas forced out of the region 87, beneath the plate 88, by the upward movement of the piston 74.

It will be noted that the rightward movement of the main valve piston 60 will close off the annular area 68 by the enlarged portion 90, which is dimensioned to just fit within the opening 67 of plate portion 91 of casting member 58.

In the fully open-circuit position of the interrupter, not shown, the operating piston 71 remains in its upper position, and the cross-bar 40 with the movable contact 77, is adjacent the lower end of the tank 1, establishing an adequate isolating gap between the contacts 76, 77.

To effect the closing operation, suitable mechanism, not shown, causes upward movement of the lift rod 41 and the cross-bar 40. The cross-bar 40, in striking the valve operating rod 44 and moving the same upwardly, compresses the spring 46, and actuates the pilot exhaust valve 53, causing the latter to close the exhaust port 54 and to open the inlet port 55. High-pressure gas, from the region 64 within the tank 1, flows through the inlet port 55 and acts against the right hand side of the piston 61. Since this gas pressure acts over the entire area of the piston portion 61, it quickly closes the main exhaust

valve 62. At the same time, the valve stem 66 moves the restricted portion 69 within the opening 67, thereby permitting high-pressure gas to pass through the open port 63, through the annular area 68, and into the region 70 on the top side of the operating piston 71. It will be obvious that the gas pressure will be equalized on both sides of the operating piston 71, and the compression spring 72 will then take over, and drive the operating piston 71 and the orifice structure 73, together with the movable contact 76, downwardly to effect engagement between the contacts 76, 77. The interrupter will then be in the closed position.

Providing the lost-motion connection 78 permits the cross-bar 40 to pick up speed before the inturned flange portion 92 picks up the flange 81 and drives the movable contact 77 downwardly.

Fig. 7 illustrates a modified type of exhaust valve arrangement, which may be substituted for the valve operating rod 44 and the pilot exhaust valve construction 53 of the interrupting unit of Fig. 6.

Referring to Fig. 7, it will be observed that a terminal bushing 94 has a magnet structure 95 associated therewith comprising a solenoid tripping coil 96, a stationary armature 97 and a movable armature 98. The movable armature 98 is linked by a rod 99 and a lever 100 to a pilot exhaust valve 101.

The pilot exhaust valve 101 operates similarly to the operation of the pilot exhaust valve 53 of Fig. 6. In other words, energization of the solenoid tripping coil 96 will effect upward movement of the movable armature 98, effecting through the linkage 99, 100 closing of the inlet port 102, and opening of the exhaust port 103. This will effect rightward movement of the main valve piston 104 in the manner previously described, the valve stem 105 having a plurality of bypassing grooves 106, which function in a similar manner to the functioning of the restricted portion 69 of the valve stem 66 in Fig. 6.

It will be noted that following extinction of the arcs drawn within the interrupters disposed within the tank 107 of Fig. 7, and deenergization of the tripping coil 96 the spring 108 will close the exhaust port 103 and open the inlet port 102. The high-pressure gas, which will now enter the region 65, will be assisted by the spring 109 to effect the leftward movement of the valve piston 104 and closing of the main exhaust port 110. The high-pressure gas will then pass through the port 63, through the grooves 106 in valve stem 105, and enter the region 70 above the operating piston 71 (Fig. 6). The spring 72 will then take over, and effect downward motion of the orifice structure 73 and hence downward movement of the movable contact 76.

During the closing operation, since the orifice structure 73 will already be at its lowermost position, as explained above, the movable contact 77 will make engagement with the movable contact 76 prior to the time of engagement of the contacts 76, 77 of the arrangement shown in Fig. 6, where the valve operating rod 44 must be moved upwardly at the extreme end of the closing stroke.

The pilot valve exhaust arrangement 93 shown in Fig. 7, operated by the trip coil 96, serves to further increase the speed of interruption, since tripping would begin immediately on closing of the trip circuit and would not require waiting for motion of the cross-arm 40.

A still further modified type of exhaust valve arrangement is disclosed in Fig. 8 of the drawings. Here the valve operating rod 44a has a pin-and-slot connection 111 with the exhaust valve stem 112. The spring 46 (Fig. 6) effects downward movement of the valve operating rod 44a upon lowering of the cross-bar 40 (Fig. 6). The spring 46 is of sufficient strength, and the exhaust valve area is of sufficiently small area, to cause downward movement of the exhaust valve 113 of Fig. 8 against the spring force exerted by a compression spring 114 and the closing force exerted by the high gas

pressure. The opening of the exhaust port 115 will effect opening of the interrupter in the manner previously described. The exhaust valve 113 has a plurality of bypassing grooves 116, which permit high-pressure gas from the region 64 within the tank 1 to flow into the region 70, when the exhaust valve 113 is in its upward position.

From the foregoing it will be observed that Fig. 8 shows a directly operated exhaust valve arrangement, 10 in which the operating rod 44a may have an opportunity to pick up speed, before opening the exhaust valve 113, because of the lost-motion afforded by the pin-and-slot connection 111 between the valve operating rod 44a and the exhaust valve stem 112.

Fig. 9 illustrates a modified type of arc-extinguishing unit, generally designated by the reference numeral 118. It will be observed that in the extinguishing units of Figs. 2, 3, 4 and 6 that the orifice structure was movable with the movable contact, and hence possessed some inertia. 20 To effect very high-speed motion of the main piston causing fluid flow, the construction illustrated in Fig. 9 utilizes a stationary orifice structure 119. In other words, in the unit 118 of Fig. 9, only the fluid-driving piston 120 is caused to move by the upward movement of the operating piston 71.

The upward movement of the piston 120 compresses gas within the region 121. A plurality of inlet tubes 122 slide with a relatively close fit through the piston 120, so that upon upward movement of the main operating piston 71, the piston 120 will force gas to flow downwardly through the inlet tubes 122 in the manner indicated by the arrows 123. This gas will flow into the orifice structure 119 comprising an orifice member 125, to effect extinction of the arc 126, established between the stationary contact 127 and the movable contact 128 carried by the extremity of the cross-bar 129.

It will be noted that Fig. 9 illustrates a modified type of directly actuated exhaust valve. A valve operating rod 130 is spring-biased downwardly by a spring 131, and is moved upwardly during the closing operation by the cross-bar 129. To eliminate the closing force upon the exhaust valve 132 if the high-pressure gas acted upon its entire lower area, we provide a bellows 133, which is sealed at its upper end to the exhaust valve 132, and which is sealed at its lower end to a lower plate portion 134 of the upper casting member 58a. Thus, the spring 131 does not have to exert a force downwardly sufficient to act against an upward force, which would be equal to the gas pressure times the total exhaust valve area. 40 As noted, atmospheric pressure exists within the region 135 within the bellows 133, so that the high-pressure gas exerts an upward closing force on the exhaust valve 132 only equal to the high-gas pressure times a differential area equal to the area of the outlet port minus the area enclosed by the bellows, rather than on the whole valve area.

Hence, a much lighter spring 131 on the valve operating rod 130 may be used, or with the same spring a much larger valve can be employed. A plurality, in this instance two, valve rods 136 mechanically interconnect the upper plate 137 of the valve operating rod 130 with the exhaust valve 132 itself. It will be noted that sealing sleeves 138 and ring gaskets 139 prevent high-pressure gas from passing along the rods 136 when the exhaust valve 132 is in its lower open position. As before, bypassing grooves 140 are provided to permit high-pressure gas from the region 64 within the tank 1 to pass along the grooves 140 into the region 70 when the exhaust valve 132 is in its upper closed position.

The operation of the modified extinguishing unit 118 will now be described. Lowering of the cross-bar 129 will serve to immediately establish an arc 126 and will at the same time permit the compression spring 131 to effect opening of the exhaust valve 132. This will exhaust the gas pressure above the operating piston 71 through the

terminal bushing, as previously explained, permitting the high-pressure gas within the region 85 to act upwardly on the operating piston 71. This will drive the piston 71 upwardly, carrying with it through the stem 141 the fluid driving piston 120. The fluid driving piston 120 will compress the gas within the region 121 and force it downwardly through the inlet tubes 122 and into the orifice structure 119, where arc extinction rapidly occurs. As long as the cross-bar 129 is in its lower position, the exhaust valve 132 remains open, and the pistons 120, 71 remain in their upper position.

During the closing operation the cross-bar 129 moves upwardly effecting engagement between the contacts 127, 128 and also causes upward movement of the valve operating rod 130 against the biasing action exerted by the compression spring 131. This will cause closing of the main exhaust valve 132, and high-pressure gas from the region 64 will then pass through the grooves 140, into the region 70 thereby enabling the compression spring 72 to take over and effect downward movement of both pistons 71 and 120. The interrupter is then in the fully closed position.

Fig. 10 illustrates a construction in many respects similar to that previously described in connection with Fig. 9 of the drawings, except that a movable contact 142 is associated with the pistons 71 and 120. In other words, the piston rod 141a carries with it a tubular movable contact 142, having an inlet passage 143 associated therewith, through which gas from the region 121 may be forced. Consequently, upon upward movement of the pistons 71, 120, in a manner similar to that previously described in connection with Fig. 9 of the drawings, the tubular movable contact 142 moves upwardly at the same time that the movable contact 128 moves downwardly. The resulting arc 126 is thereby very rapidly established, and is subjected to gas flow not only passing downwardly through the orifice member 125, but also downwardly through the inlet passage 143 associated with the movable contact 142. Spring-biased sliding finger contacts 144 press against the outer sides of the movable contact 142 to electrically interconnect the contact 142 with the metallic casting structure 145 and hence to the lower end of the terminal bushing 36.

It is believed that the manner of operation is obvious, namely that upward movement of the pistons 71, 120 together with interconnecting piston rod 141a and tubular movable contact 142 subjects the resulting arc 126 to gas flow in the manner indicated by the arrows, the gas flow passing downwardly through the inlet tubes 122 and also downwardly through the interior 143 of the movable tubular contact 142. Arc extinction is rapid, it being noted that the arc 126 is initially established on the downstream side of the orifice 125.

Fig. 11 indicates a modified type of arc-extinguishing unit 147 in which the movement of the piston 120 is reversed to that previously shown in connection with Figs. 9 and 10 of the drawings. In other words, the operating piston 71 has the gas exhausted from the region 70 below it through the holes 70a and the exhaust valve arrangement 148 which is identical to the exhaust valve arrangement 148 of Fig. 9. Consequently, the gas pressure within the region 121 is raised, so that the gas flows downwardly through the orifice 125 and adjacent the established arc 149. This construction has the advantage that the inlet tubes 122 of Figs. 9 and 10 may be eliminated. Also, a retrieving or retracting tension spring 150 serves to raise the pistons 120, 71 following the admission of high pressure gas through the grooves 140 and into the region 70 when the exhaust valve 148 is closed. This insures that at the start of any opening operation the pistons 71, 120 will be in their upper raised position.

From the foregoing description of several arc extinguishing units, it will be apparent that we have disclosed gas flow interrupting devices especially suitable for effec-

tive operation within a container filled with sulphur hexafluoride or selenium hexafluoride gas at a moderately elevated pressure. In the forms illustrated in Figs. 1-4 of the drawings, the operation resulted in no loss of the gas, which experience has shown may be used without replacement for a large number of interruptions. In other forms, such as the interrupters of Figs. 5, 6, 9, 10 and 11, some gas is discharged through the tubular bushing studs during each operation, but only that amount contained within the operating cylinders 48, which would be very small, compared with the volume of the whole breaker tank. In addition, the discharge gas does not come directly from the arcing chamber and so is cold and relatively free from arc-produced decomposition products.

15 The discharge through limited area ports of cold gas only eliminates the "clogging" difficulty, which limits the amount of hot gas which can be discharged and so may limit the currents which can be interrupted, when hot gas directly from the arc chamber must be vented through valves and ports.

20 The circuit interrupters of our invention are particularly adapted to use at least one gas selected from the group consisting of sulfur hexafluoride and selenium hexafluoride, or admixed with at least one of the group consisting of helium, carbon dioxide, air, nitrogen and argon.

25 The use of selenium hexafluoride as an arc-extinguishing medium is described and claimed in United States patent application filed September 14, 1954, Serial No. 455,976, now United States Patent 2,733,316, issued January 31, 1956, to Thomas E. Browne Jr., Albert P. Strom and Harvey E. Spindle, and assigned to the assignee of the instant application.

30 Although we have described the interrupters as being particularly suitable for use with sulfur hexafluoride gas or selenium hexafluoride gas in a tank structure, it will be noted that certain features of the invention may well be applicable to interrupters operating with other gases than sulfur hexafluoride gas or selenium hexafluoride gas. For example, the discharge of relatively cold gas, instead of hot ionized gas, may be applicable to interrupters utilizing compressed air, or other gases, such as nitrogen, hydrogen, etc. suitable for arc extinction. We do not, therefore, intend to limit our invention solely to the use of sulfur hexafluoride gas or selenium hexafluoride gas or mixtures containing these gases, since other gases may be substituted therefor with advantage, and use may be made of certain features of the invention in connection therewith.

35 Although we have shown and described specific structures, it is to be clearly understood that the same were merely for the purpose of illustration, and that changes and modifications may readily be made therein, by those skilled in the art, without departing from the spirit and scope of the invention.

40 We claim as our invention:

45 1. A circuit interrupter including a tank having a pair of terminal bushings extending therein, an arc-extinguishing unit including separable contact means for establishing an arc disposed adjacent the interior end of each terminal bushing, an arc-extinguishing gas under pressure disposed within the tank, a cross-bar for electrically interconnecting the units, said separable contact means being constantly disposed in a gaseous region under pressure, a piston structure for effecting a circulating flow only of gas under pressure against the arc established between said separable contact means, said piston structure being associated with at least one of said arc-extinguishing units, said piston structure including an operating piston for effecting the motion thereof, the gas under pressure constantly acting upon one side of said operating piston, and valve means actuated by the opening motion of said crossbar for exhausting the gas pressure from the other side of said operating piston to effect thereby opening motion of the operating piston and consequent circulating flow of gas under pressure by said

piston structure against the arc established within said one arc-extinguishing unit.

2. A gas-blast circuit interrupter including a tank filled with gas under pressure and having a hollow terminal bushing extending therein, an arc-extinguishing unit disposed adjacent the inner end of the hollow terminal bushing, said arc-extinguishing unit including a pair of separable contacts constantly disposed in a gaseous region under pressure, said pair of separable contacts being separable to establish an arc during the opening operation of the circuit interrupter, piston structure including an operating piston for causing a circulating flow only of gas under pressure against the arc, the gas under pressure constantly acting upon one side of the operating piston, and means for exhausting the gas on the other side of the operating piston through the hollow terminal bushing to effect motion of the piston structure during the opening operation.

3. A gas-blast circuit interrupter including a tank filled with gas under pressure and having a pair of terminal bushings extending therein, at least one of the terminal bushings being hollow, a pair of arc-extinguishing units disposed adjacent the interior ends of the terminal bushings, a conducting crossbar having a pair of movable contacts disposed at its outer ends and adapted to electrically connect the two units in series in the closed circuit position, piston structure for causing a circulating flow only including an operating piston and a movable contact for at least one of the units, the last-mentioned movable contact cooperating with one of the contacts of said pair to establish an arc within a unit, said pair of arc-establishing contacts being constantly disposed in a gaseous region under pressure, said circulating piston structure serving to force a circulating flow of gas against the arc in said unit, means for exhausting the gas on one side of the operating piston through the hollow terminal bushing to effect motion of the piston structure during the opening operation, and the gas under pressure constantly acting on the other side of the operating piston.

4. A circuit interrupter including a tank filled with gas under pressure and having a pair of terminal bushings extending therein, at least one of the terminal bushings being hollow, a pair of arc-extinguishing units disposed adjacent the interior ends of the terminal bushings, a conducting crossbar having a pair of movable contacts disposed at its outer ends and adapted to electrically connect the two units in series in the closed circuit position, piston structure including an operating piston for forcing gas under pressure against the arc established within one unit, valve means for exhausting the pressure back of the operating piston through said one hollow terminal bushing to cause movement of said operating piston, a valve operating rod for effecting operation of said valve means, and the cross-bar actuating the valve operating rod.

5. A gas-blast circuit interrupter including a tank filled with gas under pressure and having a hollow terminal bushing extending therein, an arc-extinguishing unit disposed adjacent the inner end of the hollow terminal bushing, said arc-extinguishing unit including a pair of separable contacts constantly disposed in a gaseous region under pressure, said pair of separable contacts being separable to establish an arc during the opening operation of the circuit interrupter, piston structure including an operating piston for causing a circulating flow only of gas under pressure against the arc, the gas under pressure constantly acting upon one side of the operating piston, a main exhaust valve piston for exhausting gas pressure from the other side of the operating piston through the hollow terminal bushing, and a pilot exhaust valve to control operation of the main exhaust valve.

6. A circuit interrupter including a tank filled with gas under pressure and having a pair of terminal bushings extending therein, at least one of the terminal bushings being hollow, a pair of arc-extinguishing units disposed

adjacent the interior ends of the terminal bushings, a conducting cross-bar having a pair of movable contacts disposed at its outer ends and adapted to electrically connect the two units in series in the closed circuit position, piston structure including an operating piston, a main exhaust valve piston for exhausting gas pressure from in back of the operating piston through the hollow terminal bushing, a pilot exhaust valve to control operation of the main exhaust valve, and means responsive to movement of the cross-bar for actuating the pilot exhaust valve.

7. The combination in a compressed-gas circuit interrupter of a tank filled with gas under pressure, a hollow terminal bushing leading into the tank, an arc-extinguishing unit disposed adjacent the interior end of the terminal bushing, means for establishing an arc within the unit, means for extinguishing the arc including a piston device, said piston device having an operating piston, a main exhaust valve piston for exhausting gas pressure from in back of the operating piston through the hollow terminal bushing, a pilot exhaust valve to control operation of the main exhaust valve, and said pilot exhaust valve being of the two-way type to close the inlet valve from the tank and to open the exhaust

valve leading out of the bushing in one position, and to close the exhaust valve and open the inlet valve to the tank in the other position.

8. The combination in a compressed-gas circuit interrupter of a tank filled with gas under pressure, a hollow terminal bushing leading into the tank, an arc-extinguishing unit disposed adjacent the interior end of the terminal bushing, said arc-extinguishing unit including a piston structure having an operating piston, the piston structure including a movable orifice and a movable contact, another movable contact, the two movable contacts being separable in a region which is constantly under gas pressure, said piston structure including the movable orifice being operable to force a circulating flow only of gas under pressure against the arc which is established between the movable contacts, the gas under pressure constantly acting upon one side of said operating piston, and exhaust-valve means for exhausting the gas pressure on the other side of said operating piston through the hollow terminal bushing.

9. The combination in a compressed-gas circuit interrupter of a tank filled with gas under pressure, a hollow terminal bushing leading into the tank, an arc-extinguishing unit disposed adjacent the interior end of the terminal bushing, said arc-extinguishing unit including a piston structure having an operating piston, the piston structure including a movable orifice and a movable contact, another movable contact, the two movable contacts being separable in a region which is constantly under gas pressure, said piston structure including the movable orifice being operable to force a circulating flow only of gas under pressure against the arc which is established between the movable contacts, the gas under pressure constantly acting upon one side of said operating piston, exhaust-valve means for exhausting the gas pressure on the other side of said operating piston through the hollow terminal bushing, and a two-way acting pilot exhaust valve for operating said exhaust-valve means.

10. A compressed gas circuit interrupter including a tank containing gas under pressure, a pair of hollow terminal bushings extending into the tank and carrying arc-extinguishing units at their interior ends, a conducting cross-bar electrically interconnecting the pair of units in series, a movable contact at each end of the cross-bar, a cooperating movable contact associated with each unit, a gas driving piston device associated with each unit, each piston device including a movable orifice member and also the cooperative movable contact for that particular unit all movable as a unit, each piston device also including an operating piston, exhaust valve means for exhausting gas on one side of each operating piston

75

65

through the hollow terminal bushing for that particular unit, and means associated with movement of the cross-bar for actuating the exhaust valve means.

11. A compressed gas circuit interrupter including a tank containing gas comprising as its essential constituent a gas selected from at least one of the group consisting of SF₆ and SeF₆ under pressure, a pair of hollow terminal bushings extending into the tank and carrying arc-extinguishing units at their interior ends, a conducting cross-bar electrically interconnecting the pair of units in series, a movable contact at each end of the cross-bar, a cooperating movable contact associated with each unit, a gas driving piston device associated with each unit, each piston device including a movable orifice member and also the cooperable movable contact for that particular unit all movable as a unit, each piston device also including an operating piston, exhaust valve means for exhausting gas on one side of each operating piston through the hollow terminal bushing for that particular unit, and means associated with movement of the crossbar for actuating the exhaust valve means.

12. A compressed gas circuit interrupter including a tank containing gas under pressure, a pair of hollow terminal bushings extending into the tank and carrying arc-extinguishing units at their interior ends, a conducting cross-bar electrically interconnecting the pair of units in series, a movable contact at each end of the cross-bar, a cooperating movable contact associated with each unit, a gas driving piston device associated with each unit, each piston device including a movable orifice member and also the cooperable movable contact for that particular unit all movable as a unit, each piston device also including an operating piston, a main exhaust valve for exhausting gas on one side of each operating piston through the hollow terminal bushing for that unit, and a two-way pilot exhaust valve controlling the main exhaust valve and responsive to movement of the cross-bar.

13. A compressed-gas circuit interrupter including a tank constituting an enclosure and containing an arc-extinguishing gas under pressure, a pair of hollow terminal bushings extending into the tank and carrying arc-extinguishing units at their interior ends, each arc-extinguishing unit having separable contact means associated therewith for establishing an arc, a conducting cross-bar electrically interconnecting the pair of arc-extinguishing units in series, a movable contact disposed at each end of the cross-bar, piston structure associated with at least one of the arc-extinguishing units and operable to force said compressed arc-extinguishing gas against an arc to effect arc extinction, an operating piston connected to said piston structure for effecting motion of the same, an operating cylinder within which said operating piston moves, the compressed gas within said tank acting at all times on one side of said operating piston, and exhaust valve means including a tripping solenoid for exhausting the compressed gas within said operating cylinder on the other side of said operating piston to the region externally of said tank through a hollow terminal bushing during the opening operation to effect thereby opening movement of the operating piston.

14. A compressed-gas circuit interrupter including a tank constituting an enclosure and containing an arc-extinguishing gas under pressure, a pair of hollow terminal bushings extending into the tank and carrying arc-extinguishing units at their interior ends, each arc-extinguishing unit having separable contact means associated therewith for establishing an arc, a conducting cross-bar electrically interconnecting the pair of arc-extinguishing units in series, a movable contact disposed at each end of the cross-bar, piston structure associated with at least one of the arc-extinguishing units and operable to force said compressed arc-extinguishing gas against an arc to effect arc extinction, said one arc-extinguishing unit including a relatively stationary orifice structure and a

relatively stationary contact which constitutes a part of said separable contact means, an operating piston connected to said piston structure for effecting motion of the same, an operating cylinder within which said operating piston moves, the compressed gas within said enclosure acting at all times on one side of said operating piston, and means exhausting the compressed gas within said operating cylinder on the other side of said operating piston to the region externally of said enclosure during the opening operation to effect thereby opening movement of said operating piston.

15. A compressed-gas circuit interrupter including a tank constituting an enclosure and containing an arc-extinguishing gas under pressure, a pair of hollow terminal bushings extending into the tank and carrying arc-extinguishing units at their interior ends, each arc-extinguishing unit having separable contact means associated therewith for establishing an arc, a conducting cross-bar electrically interconnecting the pair of arc-extinguishing units in series, a movable contact disposed at each end of the cross-bar, piston structure associated with at least one of the arc-extinguishing units and operable to force said compressed arc-extinguishing gas against an arc to effect arc extinction, said one arc-extinguishing unit including a relatively stationary orifice structure, said piston structure including a cooperable movable contact which is separable from one of the aforesaid movable contacts, an operating piston connected to said piston structure for effecting motion of the same, an operating cylinder within which said operating piston moves, the compressed gas within said enclosure acting at all times on one side of said operating piston, and means exhausting the compressed gas within said operating cylinder on the other side of said operating piston to the region externally of said enclosure during the opening operation to effect thereby opening movement of said operating piston.

16. A compressed-gas circuit interrupter including a tank constituting an enclosure and containing an arc-extinguishing gas under pressure, a pair of hollow terminal bushings extending into the tank and carrying arc-extinguishing units at their interior ends, each arc-extinguishing unit having separable contact means associated therewith for establishing an arc, a conducting cross-bar electrically interconnecting the pair of arc-extinguishing units in series, a movable contact disposed at each end of the cross-bar, piston structure associated with at least one of the arc-extinguishing units and operable to force said compressed arc-extinguishing gas against an arc to effect arc extinction, said one arc-extinguishing unit including a relatively stationary orifice structure, said piston structure including a cooperable movable tubular contact which is separable from one of the aforesaid movable contacts, an operating piston connected to said piston structure for effecting motion of the same, an operating cylinder within which said operating piston moves, the compressed gas within said enclosure acting at all times on one side of said operating piston, and means exhausting the compressed gas within said operating cylinder on the other side of said operating piston to the region externally of said enclosure during the opening operation to effect thereby opening movement of said operating piston.

17. A gas-blast circuit interrupter including means defining an enclosure containing an arc-extinguishing gas under pressure, an arc-extinguishing unit disposed interiorly within said enclosure and having separable contact means for establishing an arc, the region about said separable contact means being constantly under pressure, piston structure associated with said arc-extinguishing unit operable to force said compressed arc-extinguishing gas in a circulating flow only against said arc to effect arc extinction, and means employing the compressed gas within said enclosure to move said piston structure.

18. A gas-blast circuit interrupter including means defining an enclosure containing an arc-extinguishing gas

under pressure, an arc-extinguishing unit disposed interiorly within said enclosure and having separable contact means for establishing an arc, the region about said separable contact means being constantly under pressure, piston structure associated with said arc-extinguishing unit operable to force said compressed arc-extinguishing gas in a circulating flow only against said arc to effect arc extinction, an operating piston connected to said piston structure for effecting motion of the same, and means employing the compressed gas within said enclosure to drive said operating piston and so effect opening movement of said piston structure.

19. A circuit interrupter including means defining an enclosure containing an arc-extinguishing gas under pressure, an arc-extinguishing unit disposed interiorly within said enclosure and having separable contact means for establishing an arc, piston structure associated with said arc-extinguishing unit operable to force said compressed arc-extinguishing gas against said arc to effect arc extinction, an operating piston connected to said piston structure for effecting motion of the same, an operating cylinder within which said operating piston moves, the compressed gas within said enclosure acting at all times on one side of said operating piston, and means exhausting

5

10

15

20

the compressed gas within said operating cylinder on the other side of said operating piston to the region externally of said enclosure during the opening operation to effect thereby opening movement of said operating piston.
